UNITED STATES PATENT OFFICE.

WILLIAM B. SMITH, OF PHILADELPHIA, PENNSYLVANIA.

BAG FASTENER.

Application filed May 29, 1923. Serial No. 642,181.

My invention relates to fasteners for traveling bags and more particularly to fasteners such as are used to secure the bag on opposite sides of a centrally located locking member.

Heretofore fasteners have been made in a variety of different ways and while such fasteners have been found to be efficient, they are open to a number of objections chief among which are that they comprise a considerable number of parts which are costly to produce and assemble, and that they involve the use of springs which tend in time to weaken, thus reducing the efficiency of the fastener.

Now, in accordance with my invention, I have made available a fastener of great simplicity, comprising a minimum number of parts, which enables economic assembly, and at the same time a fastener which will be efficient and maintain its efficiency throughout the life of a bag to which it is applied.

Having now indicated, in a general way, the nature, purpose and advantages of my invention, I will proceed to a detailed description of a preferred embodiment thereof, with reference to the accompanying drawings, in which—

Fig. 1 is a perspective view of an open traveling bag equipped with fasteners embodying my invention.

Fig. 2 is a view, partly in section, showing details of construction of the fastener.

Fig. 3 is a cross-sectional view through the fastener and upper portion of the bag in closed position.

Fig. 4 is a view, partly in section, showing the relation between locking and keeper members of the fastener.

Fig. 5 indicates a traveling bag of any desired type having the suitably pivoted frame members b , b' . Secured centrally of the frame member b is a carrying handle c and a lock d , the keeper members e , e of which are carried by the frame member b' .

The fasteners embodying my invention comprise a casing f provided with flanges g , g adapted to be riveted to the frame b . In the top of the casing is a slot h through which extends a member α having formed at its lower end a hook i , which is curved to form a cam surface y and the end of which is bevelled and extends through a slot k in the frame b of the bag. The upper end of the member α is so formed as to pro-

ject at one end beyond the edge of the casing to form a finger piece l , while the other end coincides with the end of slot h . The member α is rotatably mounted on a fixed pin m , passing through the casing and secured in the side walls thereof.

Hook members n , the ends of which are bevelled as at p , are secured to the frame member b' opposite to the fasteners and form keepers for engagement by the hooks i . The operation of the device is simple. If the bag be open as shown in Fig. 1, with the member α turned on the pin n to the position shown in Fig. 1, the bag may be closed and when closed it may be secured by the fasteners by merely rotating the member α by pressure on the finger piece l , which will result in raising the hook i into engagement with the hook n . If, on closing the bag, the hook n be not aligned with hook i , the bevelled ends of the hooks will guide them into engagement and the cam surface y on hook i will draw the two frame members b and b' snugly together. The cam surface i will also tend to prevent accidental separation of the hook members i and n .

To open the bag, the hook members are separated by lifting finger piece l , which rotates member α , and hook i will be withdrawn from engagement with hook n .

Having now fully described my invention, what I claim and desire to protect by Letters Patent is:

A bag fastener comprising, in combination with a bag frame, a casing open at the bottom and having a slot in its top secured to the frame, a locking member extending through the casing and bag frame, said member having a hook formed at its lower end and having its upper end coincident with one end of the slot in the casing and extending beyond the edge of the casing adjacent the other end of the slot, said hook formed on the locking member being adapted to engage a keeper and being so formed as to exert a cam action thereon, and a pivot pin passing through said casing and locking member about which said locking member may be rotated to locking and unlocking position.

In testimony of which invention, I have hereunto set my hand, at Philadelphia, on this 25th day of May, 1923.

WILLIAM B. SMITH.
